(57) **CLAIM**

The ornamental design for a golf swing training aid as shown and described.

DESCRIPTION

FIG. 1 is a perspective view of a golf swing training aid showing my new design;

FIG. 2 is a top plan view thereof;

FIG. 3 is a bottom plan view thereof;

FIG. 4 is a front elevation view thereof, the rear being a mirror image thereof;

FIG. 5 is a right-side elevation view thereof;

FIG. 6 is a left-side elevation view thereof; and,

FIG. 7 is a perspective view of a second embodiment of FIG. 1 showing a golf swing training aid attachment, it being understood that all other surfaces are the same as those of the first embodiment.

The broken lines are included to show environment of the golf swing training aid and form no part of the claimed design.
